UNITED STATES PATENT OFFICE.

ABRAHAM B. ENNS, OF DALLAS, OREGON.

HAT-FASTENER.

SPECIFICATION forming part of Letters Patent No. 640,642, dated January 2, 1900.

Application filed October 10, 1899. Serial No. 733,183. (No model.)

To all whom it may concern:

Be it known that I, ABRAHAM B. ENNS, a citizen of the United States, residing at Dallas, in the county of Polk and State of Oregon, have invented a new and useful Hat-Pin, of which the following is a specification.

This invention relates to means for securing ladies' hats to their heads.

It is a well-known fact that the common or ordinary hat-pin operates only ineffectually to properly secure a lady's hat and also defaces or mars the crown of the hat by reason of the holes or perforations made by inserting the pin at different places.

15 The object of the present invention is to provide an effective hat-securing device which will effectually obviate the disadvantages above mentioned. It is also designed to provide an improved locking disk or plate, 20 which is fixedly attached to the crown of a hat and directs the pin always through the same opening, so as to prevent defacing of the hat, and also to provide an improved locking engagement between the hat-pin proper and 25 the locking plate or disk and at the same time facilitating the application and removal of the pin.

To these ends the present invention consists in the combination and arrangement of 30 parts, as will be hereinafter more fully described, shown in the accompanying drawings, and particularly pointed out in the appended claims, it being understood that changes in the form, size, proportion, and 35 minor details of construction may be made within the terms of the appended claims without departing from the spirit or sacrificing any of the advantages of the invention.

In the drawings, Figure 1 is a perspective 40 view showing the application of the present invention. Fig. 2 is a longitudinal sectional view thereof. Fig. 3 is a detail perspective view showing the head portion of the hat-pin. Fig. 4 is a detail perspective view of 45 the locking plate or disk. Fig. 5 is a detail elevation showing the manner of mounting the locking plate or disk. Fig. 6 is a detail perspective view of a portion of a hat-pin and showing a modification.

50 Corresponding parts of the several figures of the drawings are designated by like characters of reference.

Referring particularly to Fig. 3 of the accompanying drawings, 1 designates the ordinary straight and pointed shank of the hat-pin, having an eye 15 at its head end, connected with which through the medium of an engaging eye 16 is a pendant 2. Adjacent to this head and projecting at substantially right angles to the shank of the pin and preferably in the plane of the eye 15 is a lateral lug or shoulder 3, which is adapted to cooperate with an improved locking-plate for the purpose of locking the pin to the hat.

The means for locking the hat-pin upon a 65 hat comprises a plate 4, preferably of circular or disk-like form, ornamented in any preferred manner and provided with a central perforation 5. Surrounding this perforation or opening and located upon the outer face 70 of the plate is a convex cap 6, the inner side of which is closed by the plate and forms a hollow head. This cap or head is provided with a radial slot 7, having its inner end located centrally of the head and alined with 75 the perforation in the plate. This slot extends, preferably, upwardly toward the peripheral edge of the head and is of a length and size to readily receive the lug or shoulder on the hat-pin, although, as will be seen from 80 the following explanation, the slot may extend in any direction other than downwardly.

By reference particularly to Figs. 2 and 5 of the drawings it will be seen that the locking-plate is secured in place by means of 85 pointed prongs 8, which are provided upon the reverse side of the plate and near the peripheral edge thereof. These prongs are forced through the crown 9 of a hat, and the projecting ends thereof are embraced by a 90 suitable ring 10, the extremities of the prongs being bent outwardly so as to firmly embrace the adjacent side of the ring, as indicated at 11. Thus it will be seen that the present locking-plate may be readily attached to any hat 95 without the employment of skilled labor or specially-constructed implements.

In the operation of the device, the locking-plate being positioned as hereinbefore described, the pointed end of the hat-pin is inserted through the inner end of the slot 7, the central perforation of the plate, the crown of the hat, and into the hair of the wearer, the lug 3 passing through the slot 7 and into the

interior of the hollow cap or head 6, after which the pin is turned axially, so as to dispose the lug downwardly and away from the slot, the weight of the pendant holding the 5 hat-pin, with the lug, out of alinement with the slot, and thus preventing it from being displaced longitudinally outward. It will be noted that the lateral lug 3 when inclosed within the hollow cap or head engages the 10 opposite inner side thereof, so as to prevent accidental longitudinal movement of the hat-pin in opposite directions. To release the hat-pin, it is simply necessary to give the pin an axial turn until the lug 3 is alined with the 15 slot in the hollow head, when the pin may be readily withdrawn.

From the foregoing description it will be evident that the hat-pin is always inserted through the same opening and that as the 20 locking-plate is formed of metal the perforation therein does not wear by repeated applications of the pin, and the latter is always maintained in a comparatively rigid position. It is preferable to provide the 25 crown of a hat with a comparatively large opening 12, so as to obviate the necessity of forcing the pin through the hat, although a smaller opening may be employed. However, it is not essential that such an opening 30 be provided, as the hat-pin may be forced directly through the crown of a hat without affecting the locking of the device. The locking-plate effectively conceals whatever opening may be formed in the crown of a hat, 35 and being ornamental adds to the appearance thereof. It will also be understood that the lug and slot may have any desired location with respect to each other so long as the lug will lie away from the slot under the influence of the pendant.

In Fig. 3 of the drawings is shown a modification in which the pendant is omitted and a rigid head is substituted therefor, necessitating the turning of the pin and trying it to 45 insure the proper position of the lug.

By reference to Fig. 2 of the drawings it will be seen that the locking-plate fits flat against the exterior of one side of the crown of the hat and covers the opening 12 in the 50 latter and that the prongs 8, which extend through the crown, also surround the opening 12. Furthermore, the ring 10 fits snugly the inner side of the crown, surrounds the opening therein, and also embraces the projecting ends of the prongs, whereby the crown is firmly clamped between the locking-plate and the ring, so as to brace the crown and prevent the latter from becoming broken by the repeated application of the hat-pin.

Having thus described my invention, what I claim, and desire to secure by Letters Patent, is—

1. The combination with a hat-pin, having a lateral lug, of a fastening therefor, comprising a locking-plate, having means for attachment to a hat, and provided with a perfora-

tion, and a hollow cap or head located upon the outer side of the plate, inclosing the perforation, and having a slot alined with the said perforation, the hat-pin being received 70 through the slot and the perforation, and the lug inclosed within the cap or head, and out of alinement with the slot, the opposite inner sides of the cap or head engaging the lug and preventing longitudinal movement of the pin 75 in opposite directions.

2. In a fastening device of the class described, the combination with a locking-plate, having a central perforation, a hollow cap or head surrounding said perforation, located 80 upon the outer side of the plate, and provided with a radial slot having its inner end alined with the central perforation of the plate, pointed prongs projecting from the rear side of the plate, and a ring adapted to embrace 85 the prongs, and the extremities of the latter adapted to be bent upon said ring, of a pin having a lateral lug or shoulder, substantially as and for the purpose set forth.

3. The combination with a hat-pin, comprising a substantially long pointed shank, having an intermediate lateral lug, and a pendant located at the outer end of the shank, of a locking-plate for application to a hat, and having a perforation, and a hollow cap or 95 head located upon the outer side of the plate, inclosing the perforation therein, and provided with a slot, the inner end of the latter being alined with the perforation in the plate, the shank of the pin being received through 100 the slot and the perforation, the lug being inclosed within the hollow cap or head, and the pendant normally holding the lug out of alinement with the slot.

4. The combination with a locking-plate 105 having a perforation and adapted for attachment to a hat, of a hollow cap surrounding the perforation and having a slot alined with the perforation, a pin adapted to pass through the slot and perforation, a lug upon the pin adapted to pass through the slot and lie within the inclosure of the cap, an eye upon the pin lying at one side thereof, and a pendant connected with the eye and adapted to hold the lug out of alinement with the slot.

5. The combination with a hat, having a comparatively large opening formed in one side of the crown thereof, of a locking-plate fitted to the exterior of the crown, covering the opening therein, and having a perforation alined with the opening in the crown and of smaller diameter than said opening, a hollow cap or head located upon the outer side of the plate, inclosing the perforation therein, and provided with a slot alined with said perforation, and a plurality of fastening-prongs projecting from the inner side of the plate, extending through the crown of the hat, and surrounding the opening therein, a ring fitting snugly the inner side of the crown, encircling 120 the opening therein, and embracing the prongs, the extremities of the latter being 125 130 135

bent outwardly and embracing the ring, and
a hat-pin received through the slot, the per-
foration and the opening in the hat, and hav-
ing a lateral lug received within the hollow
5 cap or head, in engagement with opposite in-
ner sides of the latter, and out of alinement
with the slot.

In testimony that I claim the foregoing as
my own I have hereto affixed my signature in
the presence of two witnesses.
